G. A. PHILLIPS

LADDER

Filed July 29, 1925

E. R. Ruppert.

WITNESS:

G. A. Phillips INVENTOR
by Victor J. Evans ATTORNEY

UNITED STATES PATENT OFFICE.

GEORGE A. PHILLIPS, OF BRIDGETON, RHODE ISLAND.

LADDER.

Application filed July 29, 1925. Serial No. 46,838.

This invention relates to improvements in ladders, the general object being to provide an emergency ladder for use as a fire escape and which may be readily and easily 5 folded into a very compact space and yet be readily and easily applicable to a window sill whereby the user may have a quick escape from a burning building.

Another object of my invention resides 10 in the provision of the attaching or suspending means for the ladder which may be rigidly or detachably secured to some portion of a building adjacent the windows thereof whereby the said ladder may readily and 15 easily be applied thereto.

With the above and other objects in view, the invention further includes the following 20 novel features and details of construction, to be hereinafter more fully described, illustrated in the accompanying drawing and pointed out in the appended claim.

In the drawing:—

Figure 1 is an elevation of my invention.

Figure 2 is a side elevation thereof as 25 applied.

Figure 3 is a similar view showing my present invention folded.

Figure 4 is a fragmentary longitudinal 30 section taken through the meeting ends of two ladder sections and showing the means of interconnecting the ladder sections.

Figure 5 is an elevation of a modified form of my invention.

Referring to the drawing in detail, where- 35 in like characters of reference denote corresponding parts, the reference character 10 indicates hook members which are so constructed as to be readily and easily applicable upon a window sill, and are each shown 40 as being made in the formation of an L or L-shaped in order that the offset portion thereof may lie flush with the upper side of the window sill while its short extension engages the inner side thereof and the remaining long arm formed thereon extends 45 outwardly and downwardly on the outer side of the building, as clearly illustrated in Figure 2 of the drawing. The rungs 11 have their opposite end portions secured to 50 the corresponding inner sides of the hooks 10 in order that steps may thus be provided upon the said hooks 10 for the escape of the fire trapped victims.

In order to provide means upon the lower 55 and outer ends of the L-shaped hooks 10

so that the ladder may be lengthened and completed, I provide a plurality of relatively short ladder sections in the form of spaced parallel vertically disposed standards 12 having rungs 13 correspondingly mounted within their inner sides while U-bolts 14 have their respective end portions journaled or pivoted within the meeting end portions of the standards 12 with the lower ends of the L-shaped hooks 10 and 60 the corresponding and consecutive ladder sections whereby the same may be pivoted together and extending through plates 15 upon the inner sides of the ladder sections and across the meeting ends thereof 70 while fastening elements in the form of nuts 16 are secured upon the inner free ends of the U-bolts 14 whereby the said ladder sections are held against accidental displacement. 75

As clearly illustrated in Figure 3 of the drawing the said ladder sections may be folded one upon the other, the U-bolts 14 forming the hinged or pivotal connections between the respective ladder sections and 80 the said sections, as illustrated, may be folded beneath and within the L-shaped hooks 10 thus forming a frame or enclosure for the said folded ladder sections whereby the said emergency or fire exit ladder may be 85 thus placed in a minimum space adjacent a window and be readily and easily applicable to a window for the escape of the fire trapped victims.

In Figure 5 of the drawing I have illus- 90 trated a modified form of my invention which contemplates correspondingly shaped and interconnected ladder sections having standards 12', rungs 13' and U-bolts 14' forming the hinged connection between the 95 respective meeting end portions of the standards 12', as in the similar instance of the form of my invention as clearly illustrated in Figures 1 to 4 inclusive. The characteristic departure in this form of my invention 100 from the first form, as described and illustrated, is in the provision of standards 15' having their lower ends correspondingly secured to the upper free ends of the first ladder section and further including a rung 16' 105 between their inner sides while rings 17 are provided upon the upper free ends of the said standards 15'. Leading from a common ring 18 are chains 19 having their respective end portions connected to the rings 110

17 while the upper common ring 18 is fitted upon and supported by a member 20 which is within the outer wall of a building adjacent a window and which may always be applied thereto whereby the said common ring 18 may be readily and easily placed thereon for supporting the plurality of ladder sections thus hingedly connected and supported upon the lower ends of the standards 15 in the completing of the ladder, as described and illustrated.

It will thus be noted that this form of my invention, as illustrated in Figure 5 of the drawing, may also be bolted up and placed in an out-of-the-way position and ready and accessible for use and applicable to the member 20 thus placed upon the wall, not shown, of a building.

The invention is susceptible of various changes in its form, proportions and minor details of construction, and the right is herein reserved to make such changes as properly fall within the scope of the appended claim.

Having described my invention what is claimed is:—

A ladder including substantially L-shaped hooks arranged in spaced parallel relation, a pair of rungs arranged in spaced relation with their ends mounted in the vertical parts of said hooks, a plurality of relatively short ladder sections arranged in spaced pairs, a pair of spaced rungs having their ends mounted in each pair of the ladder sections, U-bolts having their ends pivotally mounted in adjacent ends of the ladder sections and with the outer end of the vertical part of the hook members whereby to pivotally connect the ladder sections to each other and the adjacent sections to the hooks, wear plates mounted upon the ends of the said plates and nuts upon the bolts normally maintaining said wear plates in operative position, the said ladder sections being adapted to be folded beneath and within the L-shaped hooks.

In testimony wherof I affix my signature.

GEORGE A. PHILLIPS.
